CLIFFORD C. CARSON, OF CLEVELAND, OHIO

METHOD OF HEATING

Application filed September 27, 1928. Serial No. 308,681.

This invention relates to a method of and apparatus for heating buildings such as factories, theaters and the like, and aims to provide means whereby indirect heating equipment may be employed efficiently to utilize the maximum heat in the breathing zone or that portion of the building where the heat is required.

In the accompanying drawings,

10 Fig. 1 is a front elevation of a unit heater capable of carrying out my method;

Fig. 2 is a sectional view taken on the line 2—2 of Fig. 1;

15 Fig. 3 is a sectional view taken on the line 3—3 of Fig. 2; and

Fig. 4 is a diagrammatic illustration, on a reduced scale, showing how my method is applied to an ordinary shop or factory building.

Since the advent of the modern types of 20 industrial and other buildings which have large working spaces or rooms and high ceilings or roofs, the problem of heating them economically and maintaining a comfortable, uniform temperature in the inhabited portions has become increasingly important. The old methods and apparatus for heating such buildings are known to be very inefficient because the heated air quickly rises above the breathing line or inhabited zone and a considerable portion of it is lost by radiation and 25 convection. The heat loss varies according to the temperature difference between the inside and outside, the size of the building, the area of the window openings and several other factors. The handbook of the American 30 Society of Heating and Ventilating Engineers states that the temperature rise per foot of height is usually more than one degree of Fahrenheit. Hence, the temperature near the roof of a building has to be raised 20° to 50° higher than that at the breathing line, depending upon the height of the roof, to maintain a comfortable temperature below the breathing line.

45 Many attempts have been made to provide heating equipment for heating industrial plants and large rooms or buildings economically. Unit heaters having fans to discharge hot air at a high velocity into the lower portions of the buildings have proven to be far

more efficient than ordinary radiator systems. Such systems are now quite common. However, they have not solved the heating problem satisfactorily because they cannot materially reduce the temperature rise per foot 55 of height. This invention provides a novel method of delivering heated air into the space to be heated and confining it to circulate below the breathing line until a very substantial portion of its heat is given up, thereby 60 reducing the temperature rise per foot of height between the floor and ceiling and, hence, the heat losses from the building or room. The ideal condition would be to confine and circulate all of the heated air below 65 the breathing line and maintain a lower temperature above it; but this cannot be accomplished without building a low ceiling.

In accordance with the improved method, heated air is delivered or discharge into the 70 space to be heated and is confined temporarily below the breathing line by simultaneously circulating relatively cold air preferably at a lower temperature and at a much higher velocity above the breathing line. The idea 75 is to create an artificial ceiling of air above the space to be heated. This is preferably done by discharging a thin and wide stream of relatively cold air at a velocity of between 1500 and 3000 feet per minute above a stream 80 of hot air discharging at a velocity of 800 to 1200 feet per minute. A velocity difference of between 500 and 2000 feet per minute will give very satisfactory results. The air in the room or building is thus practically 85 stratified and the high velocity curtain does not really yield or bend upwardly due to the natural tendency of the heated air to rise. Moreover, the curtain of relatively cold air is more dense than the heated air and exerts 90 downward pressure on it, thereby overcoming to a considerable extent the buoyant effect of expanding heated air. In fact, the curtain is practically impenetrable by the heated air until the air is dissipated and its velocity 95 diminishes considerably. It will be understood that the relative velocities, volumes and temperatures of the hot and relatively cold air will be governed by the particular heating requirements and will vary according to 100

the size of the space to be heated, the desired temperature, and other local conditions. The relative velocities and volumes are therefore controllable within the desired range. This is preferably done either by changing the speed of the fans or by varying the thickness of the air curtain or both.

The method may be practiced by using many different types of apparatus. One illustrative form of apparatus will now be described to afford a better understanding of the method.

Herein, the heated air is delivered by a well known unit heater 10 of the type which employs a fan blower 11 to discharge air through a series of heating coils from which it absorbs heat and then the air is discharged horizontally into the room or building, as the case may be. In this instance the fan 11 is arranged near the bottom of the heater and is supplied at the intake with air from the room or building. However, in some instances, fresh air from the outside is admitted.

The curtain or stratum of air above the discharging hot air may be created in a great variety of ways, but herein, there is shown a series of fan blowers 13, within a housing 14 secured above the casing of the heater 10. The housing may be made of sheet metal and has intake openings 15 providing double intakes for the fans. The fans discharge through the mouth of a hood 16 which is shown as being nozzle-shaped or flared to control the curtain stream without creating eddies.

To control the relative velocities of the heated air and the air curtain or stratum, the nozzle for the air curtain is shown as being adjustable. In the present example, the hood 16 is pivoted at the rear end to the forward end of the housing and the vertical side walls 17 thereof have a series of holes 18 adapted to register with holes in stationary brackets 19 to receive bolts or pins 20, the idea being to enlarge the nozzle to decrease the velocity of air curtain.

To guide the lower part of the curtain there is shown a curved sheet metal wall 21 suitably welded or brazed at the forward edge to the front edge of the upper wall of the heater 10, the construction being somewhat similar to that of an airplane wing. This arrangement also tends to avoid eddy currents and a resulting mixture of the relatively cold air in the curtain with the heated air.

Obviously the fans may be separately driven in any suitable manner, but herein, they are belt driven by a common motor 22 supported on a shelf or supporting bracket 23 at one side of the casing, the speed ratio being determined to suit the demands on the heating installation by using pulleys of different sizes.

In Fig. 4 one of a series of unit heaters

having the improvements applied thereto is shown in an ordinary factory building. Several heaters will be employed to create adequate circulation of hot air through large plants of this type. The separate strata of air are indicated by dotted lines to convey a general idea of the operation, no attempt being made to show deflections of the strata and local eddy currents because they differ widely in different installations.

From the foregoing description, it will be seen that the method is eminently adapted to effect economy and efficiency in heating large rooms or buildings. This is largely due to the fact that the heated air which is kept in active circulation is confined for a considerable time below the breathing line and, thus, is caused to give up the heat units therein before it rises to the ceiling or to the uppermost spaces in the room or building. Moreover, the active circulation caused by the confining air curtain or stratum discharging at a relatively high velocity enables the heaters to maintain a more nearly uniform temperature throughout the effective heating zone than has been possible heretofore by the ordinary methods of indirect heating.

Obviously, the invention is not restricted to the particular embodiment thereof herein shown and described.

What I claim is:—

1. The method of heating a large room or enclosure which consists in discharging heated air horizontally below the breathing line and discharging a thin curtain of relatively cold air at a much higher velocity above the breathing line and in the same direction as the heated air to prevent the heated air from rising therethrough before it has given up a large portion of the contained heat units below the breathing line.

2. That method of heating a large room or enclosure which comprises creating and projecting a stream of heated air into the space to be heated below the breathing line; and simultaneously creating and projecting a separate confining stream of air at a higher velocity above the discharged heated air to counteract the tendency of the heated air to rise from that portion of the space to be heated until a substantial portion of the heat is given up in said space.

3. That method of heating a large room or enclosure which comprises heating and delivering air into the space to be heated below the breathing line; and simultaneously creating and maintaining an artificial ceiling of air of greater density immediately above the breathing line to counteract the tendency of the heated air to rise from said space before it has given up a substantial portion of its heat and to reduce the temperature rise per foot of height.

4. The method of heating a large room or enclosure which consists in discharging heat-

- ed air below the breathing line and simultaneously discharging a curtain of relatively cold air at a higher velocity substantially horizontally above the breathing line to
- 5 prevent the heated air from rising therethrough before it has given up a large portion of the contained heat units below the breathing line.
5. The method of heating a large room
- 10 which consists in blowing heated air substantially horizontally into the room below the breathing line; and discharging a separate blast of air at a lower temperature in a relatively thin curtain or stratum immediately
- 15 above the stream of heated air near the floor level to confine the heated air below the curtain and prevent it from rising before some of the heat units have been given up in the space below the breathing line.
- 20 6. The method of heating a large room or building which consists in creating separate and substantially parallel strata of air; discharging one stratum above the breathing line and the other stratum into the space be-
- 25 low the breathing line; heating the lower stratum of air in the process of creation; and regulating the relative velocities of the strata so that the upper stratum will temporarily confine the heated stratum below the breathing line.

In testimony, that I claim the foregoing as my own, I have hereto affixed my signature.

CLIFFORD C. CARSON.

- ed air below the breathing line and simultaneously discharging a curtain of relatively cold air at a higher velocity substantially horizontally above the breathing line to prevent the heated air from rising therethrough before it has given up a large portion of the contained heat units below the breathing line.
5. The method of heating a large room which consists in blowing heated air substantially horizontally into the room below the breathing line; and discharging a separate blast of air at a lower temperature in a relatively thin curtain or stratum immediately
- 10 15 above the stream of heated air near the floor level to confine the heated air below the curtain and prevent it from rising before some of the heat units have been given up in the space below the breathing line.
- 15 20 25 30 6. The method of heating a large room or building which consists in creating separate and substantially parallel strata of air; discharging one stratum above the breathing line and the other stratum into the space below the breathing line; heating the lower stratum of air in the process of creation; and regulating the relative velocities of the strata so that the upper stratum will temporarily confine the heated stratum below the breathing line.

In testimony, that I claim the foregoing as my own, I have hereto affixed my signature.
